ANCHORING MEANS FOR THE CANOPY OF A COMBINATION SUN SHADE AND CLOTHES DRIER

Harry L. Griffin, New York, N. Y., assignor to Dry-Or-Shade, Inc., New York, N. Y., a corporation of New York

Application March 11, 1950, Serial No. 149,200

3 Claims. (Cl. 211—172)

1

This invention relates to anchoring means for the canopy of a combination sun shade and clothes drier.

With a combination sun shade and clothes drier, arms pivotally connected to the main post and extending radially therefrom are generally relied upon not only to support the clothes line sections but also the canopy. Difficulty has been encountered in view thereof to properly anchor the canopy in place without disturbing the clothes line sections. To this end it is an object of the present invention to provide an improved anchoring means which includes brackets secured to the inner face of the canopy and fins extending upwardly from the arms so that the clothes line sections may extend through openings in the fins; and the brackets in turn, when it is desired to position the canopy in place, may be secured to the fins without interfering in any way with the clothes line sections.

It is a further object of the present invention to provide an improved means for anchoring the canopy or awning of a combination sun shade and clothes drier to the arms of a support such as disclosed in my co-pending application for patent, Ser. No. 149,199, executed contemporaneously herewith, including fins extending upwardly from arms pivotally connected to the main post, brackets secured to the inner faces of the canopy, and set screws on said brackets frictionally to engage said fins.

It is still another object of the present invention to provide an improved means of the character described by means of which a canopy can, with facility, be secured in place when the combination sun shade and clothes drier is to be used mainly as a sun shade; and which can in turn, with facility, be manipulated to free a greater or lesser part of the canopy as desired without entirely removing the canopy from the supporting frame when the clothes line sections or any part of them are to be used for drying clothes.

These and other features, capabilities and advantages of the present invention will appear from the subjoined detailed description thereof illustrated in the accompanying drawings, in which

Fig. 1 is a fragmental enlarged side elevation partly in section showing means for anchoring the canopy in place.

Fig. 2 is a section on the line 2—2 of Fig. 1.

Fig. 3 is a plan view of a combination sun shade and clothes drier with the canopy anchored in part and liberated and moved up in 55 part.

2

Fig. 4 is an enlarged fragmental perspective showing the means for securing the anchoring bracket to the canopy.

Fig. 5 is a fragmental side elevation showing 5 the pivotal connection between the arm and the post.

Fig. 6 is a fragmental side elevation of the outer 10 end of an arm with its associated extension shown in full lines in contracted position and shown in dash and dot lines in extended position.

In the embodiment shown a plurality of arms 15 are pivotally connected to a bracket 2 on the post 3. These arms 1, see Fig. 2, have a chambered portion 4 from the upper web of which there extends the fin 5. The fin 5 is provided with a plurality of openings 6 preferably provided with eyelets or grommets to receive the clothes line sections 7. The fin 5 also serves as the abutment for the set screw 8 screw threadedly connected to the bracket 9.

The bracket 9 in the present instance is provided with a base 10 having an elongated plate portion 11 and a short plate portion 12, and having 25 intermediate thereof the parallel plate portions 13 and 14 extending normal or substantially vertical to the plate portions 11 and 12. In the present instance, the set screw 8 is screw threadedly connected in the plate portion 13, so that the free end of the set screw 8, see Fig. 2, 30 may engage the fin 5 and frictionally clamp it against the plate portion 14.

The bracket 9 is secured to the canopy 15 which is substantially rectangular in outline in the present instance, having an apron 16 extending from the free edge thereof, and an opening in the middle to receive the cap 17 of the post 3. For securing the brackets 9 to the canopy 15, four lengths 18 of cloth are secured to the inner face 40 of the canopy 15 in alignment with the arms 4. The lengths 18, see Fig. 4, each have one portion 19 engaging the inner face of the canopy 15 and two flaps 20 and 21 folded over upon the portion 19, and then secured to the canopy 15 by 45 two pairs of parallel rows of stitches 22 and 23, the flap 20 substantially corresponding to the plate 11 in length and the flap 21 substantially corresponding to the plate portion 12 in length. Obviously the stitches 22 and 23 will be made after the bracket 9 has been positioned on the portion 19 to insure a snug fit and securely anchor the bracket 9 in place on the canopy 15, so that it cannot be removed without removing the stitches.

The length 18 and bracket 9 will be positioned on the canopy 15, see particularly Fig. 1, so that

3

a part of the plate portion 11 will extend beyond the end of the arm 1 and thus spacing apron 16 from the end of arm 1 so that the control finger 24 of the device for anchoring the arm extension 25 in place will be freely accessible as shown in Fig. 1, even when the canopy 15 is anchored in place, and in turn the control finger 24 will be unmolested by the apron 16 when in the position shown in Fig. 1, so as to minimize the likelihood of accidentally actuating the finger 24 to release the extension 25. The extension 25 shown in cross section in Fig. 2 has a fin 26 extending upwardly therefrom, an enlargement 27 with slots 28 and 29 running parallel to the fin 26 and conformed to receive the flanges or ledges 30 and 31, respectively, of the chambered portion 4 of the arm 1. From the enlargement 27 there depends the extended fin 32 provided with openings having grommets 33 to receive the clothes line sections 34. In the present instance, the extension 25 has only two such grommets 33 to receive clothes line sections 34. The fin 26 is provided with two recesses or notches 35 and 36 to receive the downwardly extending projection 37 of the finger 24. The finger 24 extends beyond the outer end of the arm 1 so that the same may be depressed to actuate the finger 24 about its pivot pin 38 to raise the projection 37 out of a notch 35 or 36. When the projection 37 is disposed in the outermost notch 35 of the extension 25, the extension will be in the retracted position shown in Fig. 1 and in the full line position shown in Fig. 6. In turn, when the projection 37 rests in the innermost recess 36 of the extension 25, the extension 25 will be disposed in the outermost or extended position indicated in the dash and dot line position shown in Fig. 6.

The pin 38 on which the finger 24 is pivotally mounted, see Fig. 6, extends through the side walls of the chambered portion 4 of the arm 1. Obviously if the extended portion of the finger 24 is depressed until after the projection 37 clears the recess 36, the extension 25 may be entirely removed from slidable arrangement with the arm 4.

From the foregoing, it will appear that the fin 32 of the extension 25 constitutes a supplement for the fin 5 to support the clothes line sections 34 which are supplemental to the clothes line sections 7, and that the chambered portion 4 of the arm 1 not only serves as the support for the upwardly extending fin 5, integral therewith, but by means of its inwardly extending ledges 30 and 31 also serves as a slidable support for the supplemental fin 32 in which case advantage is taken of the stationary position of the fin 5 for an anchor by the bracket 9, and that the location of the plate 11 of the bracket 9 in outstretched position of the canopy 14, extending as it does beyond the free end of the arm 1, not only facilitates access to the finger 24 before the canopy 15 is raised, but also spaces the apron 16 of the canopy 15 from the finger 24 so that it will not be molested by the same to effect its accidental removal.

4

It is obvious that various changes and modifications may be made to the details of construction without departing from the general spirit of the invention as set forth in the appended claims.

I claim:

1. In a combination sun shade and clothes drier, the combination of a post, supporting arms pivotally connected to said post to enable them to extend outwardly therefrom, a canopy extending across said arms and supported thereby, brackets secured to the inner face of the canopy in alignment with the arms, said arms each comprising a chambered portion with opposing inwardly extending ledges at its lower face and a fin extending upwardly from its upper face, there being openings in said fin to receive clothes line sections, an extension for each arm having an enlargement slidably mounted on said ledges and a downwardly extending fin, said downwardly extending fin having openings therein to receive clothes line sections, a control finger pivotally connected to the outer end of each arm and having a portion extending beyond the free end of its associated arm, said control finger adapted to anchor said extension in extended or withdrawn position relative to its associated arm, and means for frictionally anchoring said brackets to said upwardly extending fins, one bracket for each arm, said brackets in outermost position on said arms extending beyond the free ends of said arms to support said canopy clear of said control fingers.

2. The combination as set forth in claim 1 in which said extension has an upwardly extending fin having notches therein, and said control finger has a projection at one end thereof to engage a selected one of said notches to anchor said extension in place in its associated arm.

3. The combination as set forth in claim 1 in which the outer portion of each bracket extending beyond its associated arm constitutes a plate portion.

HARRY L. GRIFFIN.
